UNITED STATES PATENT OFFICE.

TOLIVER M. JONES, OF BIRMINGHAM, ALABAMA.

LINTER-GIN-RIB MOUNTING.

Application filed March 25, 1922. Serial No. 546,672.

To all whom it may concern:

Be it known that I, TOLIVER M. JONES, a citizen of the United States of America, residing at Birmingham, in the county of Jefferson and State of Alabama, have invented 5 certain new and useful Improvements in Linter-Gin-Rib Mountings, of which the following is a specification.

My invention relates to an improvement 10 in the manner of maintaining gin saw ribs in the breast of an oil mill linter gin, or other gin.

The object of my invention more particularly is to design the ribs and the top and 15 bottom rails to which it has heretofore been the practice to bolt them so that the ribs can be very readily and easily attached and detached without the use of attaching screws in the ribs.

More particularly my object is to so design 20 the rails that the ribs will interlock with and be properly centered by the rail without relying upon the use of screws to that end.

A further object is to so mount the ribs 25 that they are held positively and rigidly in their correct operating position, thus avoiding the tendency of displacement of the ribs as their clamping screws wear, which has 30 heretofore been an objectionable operating condition.

A further object is to provide individual 35 adjustable clamps, one of which is adapted to hold each rib interlocked with both top and bottom rails, thus permitting a quick and easy removal of any desired rib.

My invention moreover comprises the 40 novel details of construction and arrangements of parts, which in their preferred embodiment only are illustrated in the accompanying drawings, to which reference is 45 made in the following specification wherein I have sought to describe my invention with sufficient particularity for those skilled in the art to practice the same.

Referring to the drawings:—

Fig. 1 is a vertical cross-sectional view 50 through the top and bottom rails of the breast of an oil mill linter gin, the saws being shown in dotted lines and the other gin parts being omitted.

Fig. 2 is a plan view partially broken away of one end of the bottom rail showing several of the ribs mounted thereon.

Fig. 3 is a cross-sectional view taken on the line 3—3 of Fig. 1.

Fig. 4 is a perspective view of a portion of one end of the top rail showing several ribs interlocked therewith.

Similar reference numerals refer to similar parts throughout the drawings.

The ribs are alike and each comprises a curved body portion 1 which may be of any standard design and shape. At its upper end the rib is provided with a top rail engaging lug 2 which in transverse cross-section is tapered so as to fit snugly between the spaced taper shoulders 3 on the top rail 4 and engage the rail. The taper seats formed on the rail between the shoulders 3 thus serve to positively and accurately center the upper ends of the ribs on the top rail 4. Each top lug 2 is provided with a shoulder 5 having a bevelled top face adapted to engage and interlock under the downwardly bevelled bottom face 6 of the top rail 4.

At its lower end each rib is provided with a bottom rail engaging lug 7 which tapers in its underside in the same manner as the lug 2 and is adapted to conform to and fit snugly into one of a series of taper seats formed in the bottom rail 8 by the countersunk recesses 9 between side taper shoulders 10. These seats are sufficiently countersunk to provide at their lower ends a shoulder 11 against which the lower end of the lugs seat squarely. The shoulders 10 project substantially above the bottom portion of the rail which is provided with a series of bolt holes 12, one in line with the center of each seat 9. 90 These holes receive screws 13 which work in elongated slots 14 in individual slide clamps 15, there being one for each of the ribs. Each clamp has its upper edge undercut by a bevelled face 16 which overlaps a correspondingly bevelled face at the bottom end of the rib lug 7.

In operation, a gin saw rib is inserted between the appropriate saws and its upper lug 2 is caused to seat between the desired shoulders 3 in the top rail and its bevel shoulder 5 is caused to interlock with the bevelled bottom edge 6 of the top rib. The lower lug 7 of the rib is then placed in its appropriate seat 9 in the bottom rail 8 and 105 by shifting its respective clamp 15 into engagement with the taper end of its lug 7 the rib can be both forced upwardly and held interlocked with the rail 8 and also clamped down against the rail 8, whereupon the 110 screw 13 is tightened and the rib is locked in position.

While this arrangement may be utilized for all ribs in the gin breast, I would prefer to have one or two ribs at each end of the breast directly attached by clamp screws to the top and bottom rails so as to hold the bottom rail in place while removing the cast iron heads of the gin. To this end I show a bolt hole provided in an end seat or seats in the top rail 4 and each 10 adapted to receive a clamp screw 17 passing through an opening therefor in the upper lug of the end rib or ribs. In like manner I provide in one or more of the end seats of the bottom rail a screw hole adapted to receive the bolt 17 and in such case the hole 12 in alignment therewith may be omitted if desired, but there will be no objection to utilizing the clamps 15 even on such end ribs which are directly bolted to 20 the top and bottom rails.

By the arrangement shown the ribs all have accurately centered seats which are all similar and these seats enable the ribs to be very quickly assembled, accurately 25 centered and positively held during operation. Also the engagement of the clamp lugs 15 forming the retaining means for the ribs will not wear and the ribs having taper interlocks in several directions at both 30 ends, the ribs will be positively and effectively held in operating position. They can be readily removed at any time by loosening their respective clamp screws 13 and letting the clamps drop away, where- 35 upon the bottom ends of the ribs can be lifted out of the base rail seats and drawn downwardly to disengage the upper lugs from the top rail. The maintenance or 40 accurately centering of the ribs and their very positive mounting give a superior grade and increased quantity of lint.

Though I have described with great particularity the details of the embodiment of the invention herein shown, it is not to be 45 construed that I am limited thereto as changes in arrangement and substitution of equivalents may be made by those skilled in the art without departing from the invention as defined in the appended 50 claims.

Having thus described my invention, what I claim as new and desire to secure by Letters Patent, is:—

1. A rib rail for gin saw breasts having individual taper rib seats formed therein.
2. A rib rail for gin saw breasts having a bevelled bottom edge and integral rib spacing means on its front face, in combination with ribs having bevelled shoulders adapted to interlock with said bevelled bottom edge and ends adapted to engage said spacing means.
3. A rib rail for gin saw breasts having spaced raised rib centering shoulders 65 thereon,

4. A rib rail for gin saw breasts having spaced rib centering shoulders thereon which taper in transverse cross-section.

5. A rib rail for gin saw breasts having a series of equi-distantly spaced tapering shoulders forming a series of taper rib seats, and having its bottom edge inclined at an angle downwardly relative to its rib engaging face.

6. A rib rail for gin saw breasts having a series of countersunk rib seats formed therein with tapering side walls.

7. A rib rail for gin saw breasts having a series of equi-distantly spaced countersunk tapering rib seats formed therein, and a clamp means adjustable to overhang the seats.

8. In combination, a rib rail for gin saw breasts having a series of rib seats, and individual adjustable rib clamps adapted to engage and secure ribs in said seats.

9. In combination, top and bottom rails for the ribs of a gin saw breast, means forming aligning rib seats in said rails, and individual slide clamps on one rail adapted to engage and secure the ribs in position.

10. In combination, a top rib rail having a bevelled edge, ribs having a top bevel shoulder adapted to interlock under said edge, and a bottom rib rail having a series of individual rib clamps adjustable to engage the ribs and force them into interlocked relation with the bevelled edge of the top rail.

11. In combination, a top rib rail having a bevelled edge, ribs having a top bevel shoulder adapted to interlock under said edge, and a bottom rib rail having a series of individual rib clamps adjustable to engage the ribs and force them into interlocked relation with the bevelled edge of the top rail, said clamps having their rib engaging ends adapted to both abut against and overhang the bottom rib ends, for the purpose described.

12. In combination, a top rib rail having a series of rib seats and a bevelled edge downwardly inclined in line with each seat, a bottom rib rail having a series of rib seats aligning with those on the top rail, ribs having end lugs adapted to fit into the top and bottom rail seats and having an undercut bevelled edge adapted to interlock under the bevelled edge on the top rail, individual rib clamps mounted on the bottom rail and adjustable to engage and hold their respective ribs interlocked with both rails, and means to secure the clamps in adjusted positions.

In testimony whereof I affix my signature.

TOLLIVER M. JONES.
